United States Patent Office

Des. 217,475
Patented May 5, 1970

217,475

SEWING MACHINE TABLE OR SIMILAR ARTICLE

Henry J. Milan, Clark, and George L. Zilg, Dunellen,
N.J., assignors to The Singer Company, New York,
N.Y., a corporation of New Jersey

Filed Feb. 5, 1969, Ser. No. 15,645

Term of patent 14 years

Int. Cl. D6—01

U.S. Cl. D33—12

Fig. 1.

Fig. 2.

Fig. 3.

Fig. 4.

Fig. 5.

Fig. 7.

Fig. 6.

FIG. 1 is a front perspective view of a sewing machine table or similar article embodying our new design;

FIG. 2 is a top plan view thereof;

FIG. 3 is a bottom plan view thereof;

FIG. 4 is a front elevation view thereof;

FIG. 5 is a side elevation view thereof as seen from the right in FIG. 4;

FIG. 6 is a rear elevation view thereof; and

FIG. 7 is a side elevation view thereof as seen from the left in FIG. 4.

We claim:

The ornamental design for a sewing machine table or similar article, substantially as shown.
